UNITED STATES PATENT OFFICE.

SAMUEL E. DUNHAM, OF NEW YORK, N. Y.

FASTENER FORMING AND DRIVING MACHINE.

1,103,404.

Specification of Letters Patent. Patented July 14, 1914.

Application filed January 8, 1908. Serial No. 409,812.

To all whom it may concern:

Be it known that I, SAMUEL E. DUNHAM, of the city of New York, borough of Brooklyn, county of Kings, and State of New York, have invented certain new and useful Improvements in Fastener Forming and Driving Machines, of which the following in a full, clear, and exact specification, such as will enable others skilled in the art to 10 which it appertains to make and use the same.

My invention relates to a mechanism for forming and driving fasteners or locks, particularly fasteners for joining two sections 15 of wood to each other.

It is especially useful in the manufacture of wooden articles requiring two or more sections of wood to be joined together, for example, in the construction of boxes, pack- 20 ing cases, picture frames, etc.

It further relates especially to the construction of fasteners or locks from sections of sheet metal, which are automatically severed into the necessary length and simultaneously crimped at the ends so that the crimped or corrugated ends will securely hold in the wood or other material into which the fasteners are driven.

In its general organization, the apparatus 30 embodies a plunger head which is periodically operated, manually or otherwise as desired, and which, by a peculiar gearing, imparts the necessary motion to a prime mover shaft which actuates successively devices for feeding the stock, preferably from a roll of metallic ribbon, a set of dies for corrugating the stock; a knife for cutting off the stock to the desired length; a plunger which drives the fastener or lock thus formed and which 35 is attached to, and moves with, the plunger head; and a set of holder jaws which receive the fastener as it is formed and hold it during the driving operation.

The apparatus may be constructed of any 45 number of units, to form and drive one or more fasteners simultaneously. As here illustrated, it is shown with two units, although of course this may be varied indefinitely.

50 My invention involves various other features of importance, all of which will be fully set forth hereinafter and particularly pointed out in the claims.

Reference is had to the accompanying drawings, which illustrate, as an example, 55 one manner of practically embodying the principles of my invention, in which drawings,

Figure 1 is a front elevation of the machine with parts broken away; Fig. 2 is a 60 plan view from below the plunger head showing particularly the stock rolls, the feeder devices and the prime mover shaft; Fig. 3 is a side elevation of the machine with the feeder guide-way in section; Fig. 4 is a fragmentary plan view with parts in section illustrating the feeder and the dies for corrugating the stock; Fig. 5 is a vertical section on the line 5—5 of Fig. 3, particularly illustrating the devices for holding the fastener, 65 and the plunger by which the fastener is driven home; Fig. 6 is a sectional plan on the line 6—6 of Fig. 5; Fig. 7 is a detail of the race cam which operates the feed; Fig. 8 is a detail of the rack and pinion and the 70 ratchet motion by which the prime mover shaft is driven from the plunger head; Fig. 9 is a section of the same devices; Fig. 10 is a view illustrating the manner of driving the fastener to join together two sections of 75 wood or other material; and Fig. 11 is a detail section of the fastener, showing particularly the sharpened edge thereof.

The machine in practice is provided with 80 a suitable base, which supports two columns 85. The base is not shown in the drawings. With the base is associated a treadle mechanism or other device for imparting the necessary motion to the plunger head.

In Figs. 1 and 2, 16 indicates a connection 90 of any desired sort to the treadle mechanism or other device for operating the plunger head. The plunger head is mounted to slide on and between the columns 15, and it comprises a body 17, with a horizontally extending or overhanging arm 18. This arm has a guide-way 19 and in the guide-way are adjustably mounted blocks 20, which carry the plungers 21. These plungers are adjustable 95 toward and from each other so that they may be suited to the position of the fastener forming and holding devices and, moving with the plunger head, serve to drive home the fasteners after they are formed, all of which will be fully set forth hereinafter. 100 Attached to, and dependent from, the over- 105

hanging arm 18 of the plunger head is a rack 22. This rack meshes with a pinion 23 loose on the prime mover shaft 24, as shown best in Figs. 8 and 9. Fastened to the pinion 23 is a disk or carrier 25 which mounts spring pressed pawls 26. These pawls engage with the shouldered collar 27, which is keyed to the prime mover shaft 24. The shaft is mounted to rotate in boxes 28 secured to a frame 29 which projects horizontally from the stanchions 15, and the arrangement of the pawls 26 and shouldered collar 27 is such that on the downward motion of the plunger head, the pawls will run idly over the shouldered collar and upon the upward motion, the pawls move toward the shoulders on the collar, but do not contact therewith and drive the collar and shaft until the plungers 21 clear the fastener-forming devices, at which time the pawls strike the shoulders on the collar and the collar and shaft 24 take up the rotation of the pinion 23 and disk 25, so that motion is imparted to the prime mover shaft, from which motion the fastener forming devices are operated. In this connection it will be seen that the shouldered collar 27 is in the nature of a ratchet, the ratchet having, however, two teeth and the parts being so disposed that a sufficient lost motion occurs to allow the plungers to clear the fastener forming devices on the upward motion of the plunger head before the fastener forming devices are set in operation. Secured to rotate with the prime mover shaft 24 is a race cam 30, in which operates the pin 31 (see Fig. 7) of a yoke 32 secured to or formed integral with a reach-rod 33. The reach-rod projects horizontally rearward (see Fig. 2) and is joined to a cross-head bar 34. This bar operates the feeder devices.

The mechanism shown in the drawings is adapted for forming two fasteners simultaneously, and hence there are two feeder devices. Obviously, however, the cross-head bar could be extended indefinitely and caused to operate any number of feeder devices, according to the number of fasteners which the machine is adapted to drive, in which case the mechanism is simply duplicated for each fastener.

According to the structure shown in the drawings, each end of the bar 34 carries a collar 35, and these collars have arms 36 projecting therefrom and pivoted to the feed dogs 37. These dogs are arranged in pairs and are themselves pivoted on a carrier block 38, which is adapted to slide horizontally in a guide 39 projecting from the frame 29. The stock is carried on reels 40, which are in number one for each fastener that the machine is adapted to form. The stock is in the form of steel ribbons wound

in a roll on the reels 40, and the feed dogs 37 work at opposite sides of the stock, pinching the stock between their points and feeding it forward with each forward motion of the cross-head bar 34 and its connections. As the cross-head bar moves backward, it will be seen that the feed dogs will be turned on their pivots to move away from the stock and then the carrier block 38 will move backward in the slide-way 39. Upon reverse motion of the cross-head bar 34, however, the feed dogs will be returned to their engagement with the stock, and then they will move forward with the carrier block 38, the stock being gripped between the feed dogs and being drawn forward by the same. The stock being fed in this manner, is passed into the devices for stamping or corrugating and cutting the fastener. As will be readily understood, these devices are duplicated for each fastener which the machine is adapted to form. In a duplex machine such as shown in the drawings, there are two duplicate sets of cutting and stamping or die devices, and to avoid confusion only one will be specifically described, the description of one applying equally to the other.

As shown best in Fig. 4, the jaws of the die are two in number and are designated 41 and 41', of which the jaw 41 is stationary, and 41' is the movable member. The stationary member is adjustably held in a part of the frame 29 by means of set screws 42, and the movable member 41' is adapted to slide in said frame toward and from the stationary member. 43 indicates the shear blade for cutting off the stock, and this works in the frame 29 against a ledger blade 44. These blades are placed immediately ahead of the jaws 41 and 41', so that as the stock is fed by the dogs 37, it is projected between and is corrugated by the jaws of the die, (the shear blade being withdrawn as shown in Fig. 4) and immediately thereafter the shear blade advances, strokes over the ledger blade, and severs the stock into the desired length, as Fig. 4 illustrates. It will be apparent, however, that this order of first corrugating and then severing the stock may be reversed, without departing from the spirit of my invention. The movable member 41' of the die is actuated by a lever 45 suitably fulcrumed on the frame at 45' and is driven by the cam 46 secured to the shaft 24, while the shear blade 43 is driven through a lever 47, fulcrumed as at 47', and is actuated by a cam 48 on the prime mover shaft 24, said lever 45 and die member 41' and said lever 47 and shear blade 43 being returned to their normal or inoperative positions by the cams 48 and 48' respectively, although it is obvious that these return movements may be effected by means of

springs. In this manner the stock is fed, corrugated and severed into lengths by a series of rapidly successive operations.

Referring now to Fig. 5, which shows suitable dies in vertical sections, it will be seen that above these dies is a guide-way 49, forming part of the frame 29, and through this guide-way the before described plungers 21 are adapted to operate. Below the dies 41 and 41' are arranged the holder jaws 50 and 51, of which the jaw 50 is stationary and the jaw 51 is movable and held yieldingly in active position by means of the spring 52, the tension of which may be 15 adjusted by the set screw 53. As shown in Fig. 6, the movable holder jaw 51 is suitably mounted in the frame 29 and guided by rods 54 although this is a detail of construction which is in no sense material. Below these 20 holder jaws 50 and 51 is a work table 55. This is supported on the column 15 and may be adjusted by means of set screws 56 to adapt it to the position of the work. The work is indicated in Fig. 5 by the 25 broken lines 57. When the fastener is formed by the devices shown in Fig. 4, the plunger head should thereupon descend, either automatically in the event that the machine is of an automatic character, or by 30 hand or foot power, in the event that the machine is adapted to be manually driven. Upon the descent of the plunger head, the plunger or plungers 21 move through the guide or guides 49, pass between the dies 41 and 41', engage the fastener and drive the same downward. At this time the fastener passes between the spring holder jaws 50 and 51, which yield to allow the motion of the fastener but which, nevertheless, press 35 against the same with sufficient firmness to hold it true during the driving operation. The continuing motion of the plunger or plungers carries the fastener through the holder jaws 50 and 51, the jaw 51 yielding 40 to allow the plunger also to pass between the holder jaws and thereupon the fastener is driven into the work, which is indicated at 57 in Fig. 5.

Fig. 10 shows an example of the work, 50 which is there supposed to consist of two sections of wood to be united by the fastener driven into them. Obviously the machine may operate on a great many different kinds of work, that illustrated in the figure being 55 offered merely as an example.

The organized operation of the machine may therefore be traced as follows: The stock having been placed upon the reels 40 and the ends of the stock projected between 60 the feed dogs 37 and the table 55 adjusted to the nature of the work which is placed thereon, upon the first downward motion of the plunger head—assuming no previous operation of the machine—the plungers will 65 descend idly, and upon the return of the

plunger head, brought about by a spring or otherwise, the shaft 24 picks up the rotation of the pinion 23 through the medium of the pawl and ratchet devices heretofore described, and the first result of this motion is 70 a backward motion of the feeding dogs, which is immediately followed by a forward motion of the feeding dogs, with the stock firmly held thereby, resulting in projecting the ends of the stock between the shear and 75 ledger blades 43 and 44 and between the die jaws 41 and 41', whereupon the movable jaw 41' advances against the stationary jaw 41, corrugating the stock and immediately thereafter the shear blade strokes over the 80 ledger blade, severing the stock as shown in Fig. 4 and completing the fastener. At this time the operation of the mechanism brought about by the upward motion of the plunger head ceases and the fasteners thus 85 formed are ready to be driven home. The operator then brings about a descent of the plunger head, which drives the plungers first through the guides 49 thence between the dies 41 and 41', which by this time will 90 have returned to their open position, the plungers then engaging the fasteners and forcing them downward through the jaws 50 and 51 into the work. This completes a single operation of the mechanism, and the 95 plunger head, with its plungers, thereupon returns to its elevated position, resulting in the formation of a second fastener as above described.

Having thus described my invention, what 100 I claim as new and desire to secure by Letters Patent of the United States is:

1. In a machine for corrugating, cutting up and driving strips of metal into wood, the combination of means acting to feed a 105 metallic ribbon, opposing dies capable of acting on said metallic ribbon to corrugate the same, means for severing the metallic ribbon into lengths, means for driving the fastener thus formed edgewise into wood and 110 opposing flat faced jaws, of which one is yielding, said jaws being located below the dies and arranged to hold the fastener during the driving operation.

2. In a machine for making and driving 115 corrugated sheet metal fasteners, the combination of corrugating dies for forming a fastener, a yielding means arranged to receive the fastener from the dies during the driving operation and a plunger operating 120 between the dies and said yielding means to drive the fastener edgewise into wood.

3. A fastener forming and driving mechanism, comprising dies for corrugating the fastener stock, of which dies one is movable, 125 means for operating the movable die, shear and ledger blades juxtaposed to the dies, means for operating the shear blade for the purpose specified, a plunger acting between the dies and arranged to drive the fastener 130

edgewise into wood, and yielding devices below the dies to receive and hold the fastener during the driving operation.

4. A fastener forming and driving mech-

- 5 anism, comprising dies for corrugating the fastener stock, of which dies one is movable, means for operating the movable die, shear and ledger blades juxtaposed to the dies, means for operating the shear blade for the 10 purpose specified, a plunger acting between the dies and arranged to drive the fastener edgewise into wood, and yielding devices below the dies to receive and hold the fastener during the driving operation, such devices 15 consisting in a stationary and a spring pressed jaw.

5. A fastener forming and driving mech- 20 anism, comprising a plunger head, a plunger carried thereby and arranged to drive the fastener edgewise into wood, and devices for corrugating the fastener stock and cutting the same into suitable lengths to form a fastener, such corrugating and cutting de- 25 vices being actuated by the return motion of the plunger head.

6. A fastener forming and driving mech- 30 anism, comprising a plunger head, a plunger carried thereby and arranged to drive the fastener edgewise into wood, fastener forming devices, and a gear for actuating the fastener forming devices from the motion of the plunger head, such gear being idle on the active stroke of the plunger and having delayed operation upon the return 35 stroke of the plunger, to permit the plunger to clear the fastener forming devices before the operation thereof.

7. In a machine for making and driving metal fasteners edgewise into wood, the 40 combination of devices for corrugating a strip of sheet metal, devices for cutting said strip into suitable lengths, means for driving the fastener thus formed into wood, a feed device for feeding the strip of sheet metal to the corrugating, cutting and driving devices, said feed device comprising a 45 slide, feed dogs pivoted thereon, and ar- ranged to oppose each other in operation, and an actuating device having operative connection with said feeding devices.

8. In a fastener forming and driving mechanism, the combination of devices for feeding a strip of sheet metal, devices for corrugating said strip comprising dies juxtaposed to each other, of which dies one is 55 movable, a lever arm connected with the movable die to operate the same, a prime mover shaft, means carried by the prime mover shaft to actuate the lever arm, means for actuating the prime mover shaft, devices for cutting the metal strip into suitable lengths to form a fastener, and means for driving the fastener edgewise into wood.

9. In a fastener forming and driving 60 mechanism, the combination of devices for

feeding a strip of sheet metal, devices for corrugating said strip, devices for cutting said strip into suitable lengths to form a fastener, said devices comprising cutting blades juxtaposed to each other, of which 70 blades one is movable, a lever arm connected with the movable blade to operate the same, a prime mover shaft, means carried by the prime mover shaft to actuate the lever arm, means for actuating the prime mover shaft, 75 and means for driving the fasteners edgewise into wood.

10. In a machine for making and driving metal fasteners, the combination of devices for corrugating a strip of sheet metal, de- 80 vices for cutting said strip into suitable lengths to form fasteners, means for driving the fastener home, feed devices for feeding the metal strip to the corrugating, cutting and driving devices, said feed devices com- 85 prising a reciprocating cross head, a sliding carrier, feed dogs pivotally connected to the cross head and also pivotally connected to the sliding carrier, a prime mover shaft, means to impart intermittent reciprocating 90 motion to the feed device from the prime mover shaft, a plunger head, and means to actuate the prime mover shaft from the motion of the plunger head.

11. In a machine for making and driving 95 fasteners, the combination of devices for feeding the fastener stock, a plunger head, a plunger carried thereby and arranged to drive the fastener home, a rack carried by the plunger head, a prime mover shaft, a 100 pinion loose thereon and meshed with the rack, pawl and ratchet devices for imparting intermittent rotary motion to the prime mover shaft through the pinion from the motion of the plunger head, corrugating dies 105 and cutting blades juxtaposed to each other and operated from the prime mover shaft, said feeding devices comprising a slide, feed dogs pivoted thereto and arranged to oppose each other in operation, and means for 110 actuating said feed device from the prime mover shaft.

12. In a machine for making and driving sheet metal fasteners, the combination of de- 115 vices for feeding the fastener stock, devices for forming the fastener therefrom, a plun- 120 ger head, a plunger carried thereby and ar- ranged to drive the fastener home, a rack carried by the plunger head, a prime mover shaft, a pinion loose thereon and meshed with the rack, pawl and ratchet devices for imparting through the pinion intermittent rotary motion to the prime mover shaft from the motion of the plunger head, said feeding 125 devices comprising a slide, feed dogs pivoted thereto and arranged to oppose each other in operation, means for imparting intermit- 130 tent reciprocating motion to the feed devices from the prime mover shaft, such means comprising a reach rod, a yoke connected

with the reach rod and a race cam carried by the prime mover shaft, and means operatively connecting said yoke with said prime mover shaft.

- 5 13. In a machine for making and driving corrugated sheet metal fasteners, the combination of a feed device for feeding the fastener stock, said feed device comprising a sliding carrier, feed dogs pivotally connected thereto and arranged to oppose each other in operation; corrugating dies juxtaposed to each other, of which dies one is movable, a lever arm connected to the movable die to operate the same; cutting blades juxtaposed to each other and to the corrugating dies of which blades one is movable, a lever arm connected to the movable blade to operate the same; a plunger head; a prime mover shaft; means carried by the prime mover shaft to actuate the lever arm for operating the corrugating dies and cutting blades respectively; means carried by the prime mover shaft to actuate the feed device; operative means connecting the prime mover shaft with the plunger head for actuating the prime mover shaft from the motion of the plunger head; and means for driving the fastener from the motion of the plunger head.
- 30 14. In a fastener forming and driving mechanism, the combination of devices for feeding the stock and forming the fasteners, a plunger head, a plunger carried thereby, and arranged to drive the fastener home, a prime mover shaft, devices for actuating said stock feeding and fastener forming devices from the prime mover shaft and means for driving the prime mover shaft from the motion of the plunger head.

- 40 15. In a fastener forming and driving mechanism, the combination of devices for feeding the stock and forming the fastener, a plunger head, a plunger carried thereby, and arranged to drive the fastener home, a prime mover shaft, devices for actuating said stock feeding and fastener forming devices from the prime mover shaft, and means for driving the prime mover shaft from the motion of the plunger head, said means for driving the prime mover shaft being inactive on the active stroke of the plunger.

- 45 16. In a fastener forming and driving mechanism, the combination of devices for feeding the stock and forming the fastener, a plunger head, a plunger carried thereby, and arranged to drive the fastener home, a prime mover shaft, devices for actuating said stock feeding and fastener forming devices from the prime mover shaft, and means for driving the prime mover shaft from the motion of the plunger head, said means for driving the prime mover shaft being inactive on the active stroke of the plunger, and having delayed operation upon the return stroke, to permit the plunger to clear

the fastener forming devices before the operation thereof.

17. In a fastener forming and driving mechanism, the combination of means for feeding the stock and forming a fastener, a plunger head, a plunger carried thereby, and arranged to drive the fastener, a prime mover shaft for actuating the stock feed and fastener forming means, a rack carried by the plunger head, a pinion loose on the prime mover shaft and meshed with the rack, and pawl and ratchet devices for driving the shaft from the pinion upon the return motion of the plunger head.

18. In a machine of the class described, the combination of devices for feeding a sheet metal strip, dies for corrugating a section of the said strip, blades for cutting the strip into suitable lengths and thereby forming a fastener, means for holding the fastener in position during the driving operation; a plunger head, a plunger carried thereby; a rack carried by the plunger head, a prime mover shaft, a pinion loose thereon and meshed with the rack, a carrier disk fastened to the pinion, a collar keyed to the prime mover shaft, pawl and ratchet devices on said carrier disk and said collar for imparting intermittent rotary motion to the prime mover shaft, and means on the prime mover shaft for imparting intermittent reciprocating motion to the feeding devices and to actuate the corrugating dies and cutting blades.

19. In a machine of the class described, the combination of a plunger head, a rack carried by the plunger head, a prime mover shaft, a pinion loose on the prime mover shaft and meshed with the rack, a carrier disk fast to the pinion, a shouldered collar keyed to the prime mover shaft, the collar having ratchet teeth to be engaged by the pawl on the carrier disk and thereby impart intermittent rotary motion to the prime mover shaft through the pinion, from the motion of the plunger head, devices acting to feed a sheet metal strip, a yoke and reach rod to impart intermittent motion to said feeding devices, a race cam on the prime mover shaft to operate the yoke and reach rod; corrugating dies acting to corrugate a section of the sheet metal strip; cutting blades to sever the corrugated section and thus form a fastener; lever arms for operating the corrugating dies and cutting blades respectively; jaws for holding the fastener in position during the driving operation; cams on the prime mover shaft to operate the lever arms; and a plunger carried by the plunger head and arranged to drive the fastener into the material to be fastened.

20. In a machine for making and driving sheet metal fasteners, the combination of devices for feeding the stock, dies capable of acting on the stock to deflect and thus

form curves, angles or corrugations therein, means for severing the stock into lengths, means for automatically driving the fastener edgewise into wood, and devices for 5 yieldingly holding the fastener during the driving operation.

In testimony whereof I have signed my

name to this specification in the presence of two subscribing witnesses.

SAMUEL E. DUNHAM.
